WINDER DRIVE

James K. Douglas, Shorewood, Wis., assignor to
The Oilgear Company, Milwaukee, Wis., a corporation of Wisconsin

Application July 3, 1939, Serial No. 282,649

22 Claims. (Cl. 242—75)

This invention relates to drives of the type employed to drive a winder which winds sheet material into rolls, and it relates in particular to a hydraulic drive which includes a rotary hydraulic motor for driving the winding shaft or drum on which the material is wound, a pump for supplying liquid to the motor to energize it, and means for varying the relative displacements of the pump and the motor to thereby decrease the speed of the winding shaft or drum as the roll of material thereon increases in diameter.

In winding sheet material into a roll as it is delivered by a machine, it is essential that the sheet be kept under tension in order to prevent it from wrinkling or buckling and in order to form a roll of the desired density, and it is very often essential that the tension on the sheet be varied in response to a variation in the linear speed of the sheet or in response to the roll increasing in diameter or to both of these factors.

The present invention has as an object to provide a drive of the above character with means for enabling it to keep the tension on the sheet within closer limits than was heretofore possible.

Another object is to provide a hydraulic winder drive with means for compensating for the friction of the winding machine and the internal friction of the winder motor.

Another object is to provide a hydraulic winder drive with means for varying the tension on the sheet in response to a variation in the linear speed of the sheet.

Another object is to provide a hydraulic winder drive with means for varying the tension on the sheet in response to the sheet accumulating upon the winding shaft.

Another object is to provide a hydraulic winder drive with means for increasing the torque of the motor during acceleration of the sheet.

Other objects and advantages will appear from the description hereinafter given of winder drives in which the invention is embodied.

According to the invention in its general aspect and as ordinarily embodied in practice, the winder drive includes a variable displacement rotary hydraulic motor for driving the winder, a first pump which discharges liquid at a rate proportional to the speed at which the sheet is delivered to the winding shaft, a second pump which discharges liquid at a constant rate, pressure channels for directing liquid from both pumps to the motor to energize it, a tension control valve which maintains pressure in the pressure channels and permits the escape therefrom of the liquid discharged by the pumps in excess of the liquid required to drive the motor, return channels connecting the outlet of the motor to the intake of the first pump whereby that pump meters the outflow from the motor and thereby governs the rate at which the motor can discharge liquid,

and means responsive to variations in the pressure in the return channel for varying the displacement of the motor whereby the motor displacement is increased with a resultant increase in motor torque and decrease in motor speed as the roll of material on the winding shaft increases in diameter.

The invention further provides means for extracting liquid at a limited rate from the return channel to thereby increase the motor displacement sufficiently to compensate for the friction in the winding machine and in the motor, means for adjusting the tension control valve to cause a greater pressure to be created in the pressure channels and thereby enable the motor to exert a greater torque when accelerating the winding machine, means for adjusting the tension control valve in response to a variation in the linear speed of the sheet, and means for adjusting the tension control valve as the roll of material on the winding shaft increases in diameter.

The invention is exemplified by the winder drives shown schematically in the accompanying drawings in which the views are as follows:

Fig. 1 is in part a diagrammatic view showing the invention embodied in a drive, which is employed to drive a machine for winding a substantially continuous sheet of flexible material into a roll as fast as it is delivered by another machine, and in part a diagram of the hydraulic circuit of the drive, the several parts being shown in the positions occupied when the drive is idle and the drive being shown provided with a throttle valve the function of which is to cause the drive to vary the tension on the sheet in response to a variation in speed.

Fig. 2 is a view showing a control valve in the position occupied when the drive is in operation.

Fig. 3 is a view showing an acceleration valve in a position different from that shown in Fig. 1.

Fig. 4 is a view showing the drive provided with a valve which may be used instead of the throttle valve shown in Fig. 1, only a part of the circuit being shown as the drive is otherwise the same as the drive shown in Fig. 1.

Fig. 5 is a view similar to Fig. 1 but showing a resistance valve substituted for the throttle valve in order that the tension on the sheet may be varied in response to the roll increasing in diameter.

Fig. 6 is a view showing a method different from that shown in Fig. 5 for varying the tension on the sheet in response to the roll increasing in diameter, only a part of the drive being shown as the remainder is substantially the same as shown in Fig. 1.

Fig. 7 is a view similar to Fig. 6 but showing the drive provided with means for varying the tension on the sheet in response both to variations in speed and variations in roll diameter.

Fig. 8 is a view similar to Fig. 4 but showing the drive provided with means for increasing the torque of the winder motor during acceleration.

Fig. 9 is a view similar to Fig. 1 but showing the drive provided with a motor having means for adjusting the tension control valve in response to the motor being accelerated or decelerated.

Fig. 10 is a central vertical section through one end of the motor shown in Fig. 9.

Fig. 11 is a section taken on a line 11-11 of Fig. 10.

Fig. 12 is a top plan view of the parts shown in Fig. 11.

Fig. 13 is a section taken on a line 13-13 of Fig. 11.

For the purpose of illustration, the invention has been shown applied to a winder for winding paper into rolls as it is delivered by a machine but it is to be understood that the invention is not limited to such use as it is susceptible of wide application.

Figs. 1 to 3

Since the winder and the paper delivering machine form no part of the present invention, the winder has been represented by a winding shaft 1 on which a substantially continuous strip of paper 2 is wound into a roll 3 as it is delivered by a machine 4 which has been represented by a stand of rollers.

Machine 4 is connected to a prime mover (not shown) through a suitable drive 5-6 and a transmission 7 having a lever 8 to control it. When lever 8 is in the position shown in full lines, transmission 7 is in neutral and machine 4 will be idle. When lever 8 is shifted to the position shown in dotted lines, transmission 7 will transmit motion from the prime mover through drive 5-6 to machine 4 to drive it. The speed of machine 4 may be varied between zero and maximum in any suitable manner as by varying the speed of the prime mover.

Shaft 1 is connected by a suitable drive 9 to a variable displacement hydraulic motor 10 which may be of any suitable type. As shown, motor 10 is provided with a displacement varying member or slide block 11 which is adapted to be moved in one direction by a piston 12 connected thereto and fitted in a stationary cylinder 13 and is adapted to be moved in the other direction by a piston 14 connected thereto and fitted in a stationary cylinder 15.

Liquid for engingeing motor 10 is supplied thereto from two pumps 16 and 17 through a branched pressure channel 18 which connects the outlets of both pumps to the inlet of motor 10. Pump 16 is driven from a power source not shown at a substantially constant speed when the drive is in operation, and pump 17 is driven in unison with machine 4 at a speed proportional to the speed of paper 2 as by being connected by a suitable drive 19 to drive 6.

Except for a very small volume which passes through a friction compensation pump to be presently described, the entire volume discharged by motor 10 passes through pump 17 which functions as a meter and thereby controls the stroke of motor 10 as will presently be explained. Consequently, pump 16 need supply to motor 10 only sufficient liquid to compensate for leakage losses, compressibility of the liquid and deflection of the parts and to create the pressure necessary to enable motor 10 to drive shaft 1.

The liquid discharged by pump 16 in excess of the liquid required by motor 10 is discharged

through a hereinafter described tension control valve 20 which resists the discharge of liquid therethrough and thereby enables pump 16 to supply liquid to motor 10 at the pressure necessary to enable motor 10 to drive winding shaft 1. 5

Pump 16 is supplied with liquid by a gear pump 23 which is driven in unison therewith and ordinarily arranged in the casing thereof according to the usual practice but which has been shown as being separate therefrom. As shown, 10 gear pump 23 draws liquid from a reservoir 24 and discharges it into a branched supply channel 25 having one branch thereof connected to the stroke control cylinder 13 on motor 10 and another branch thereof connected to the inlet of 15 a relief valve 26 through which gear pump 23 discharges liquid at all times into a branched low pressure channel 27 having one branch thereof connected to the intake of pump 16. Relief valve 26 is adapted to open at a low pressure, for instance 35# per square inch, and it is of the type that is unaffected by the pressure at its outlet so that it enables gear pump 23 to maintain in channel 25 a pressure determined by the adjustment of relief valve 26. 25

The liquid discharged by pump 23 into channel 27 in excess of requirements is exhausted through a relief valve 28 which has its inlet connected to channel 27 and its outlet connected to a drain channel 29 which discharges into reservoir 24. 30 Relief valve 28 is adapted to open at a low pressure, for instance 30# per square inch, so as to enable gear pump 23 to maintain in channel 27 a pressure equal to the resistance of relief valve 28. 35

The operation of motor 10 is under the control of a control valve 33 which is fitted in a valve casing 34 and connected by a link 35 to lever 8 so that it is shifted from the position shown in Fig. 1 to the position shown in Fig. 2 40 when lever 8 is shifted to the dotted line position to thereby cause machine 4 to be driven.

Control valve casing 34 has five annular grooves or ports 36, 37, 38, 39 and 40 formed in the wall of the bore thereof. Ports 36 and 40 45 have low pressure channel 27 connected thereto, port 37 is connected to high pressure channel 18 by a channel 41, port 39 is connected by a return channel 42 to the outlet of motor 10, and port 38 is connected to a return channel 43 which 50 may be connected directly to the intake of pump 17 but which has been shown connected to the inlet of a throttle valve 44 the outlet of which is connected by a channel 45 to the intake of pump 17. 55

Return channel 42 is also connected to the inlet of a high pressure relief valve 46 which has its outlet connected to low pressure channel 27 and through which motor 10 discharges when valve 33 is shifted to the position shown in Fig. 1 60 to stop the winder, relief valve 46 functioning as a brake to stop motor 10 and winding shaft 1 smoothly and quickly.

When motor 10 is discharging through brake valve 46, no liquid is returned from motor 10 to 65 pump 17. Therefore, in order that pump 17 may at such time draw liquid from reservoir 24 and in order that gear pump 23 may be used to initially fill the hydraulic circuit, drain channel 29 is connected to low pressure channel 27 70 through a check valve 47 and low pressure channel 27 is connected through two check valves 48 and 49 to channels 18 and 45 respectively, check valve 47 permitting liquid to be drawn from channel 29 into channel 27 and check valves 48 75

and 49 permitting liquid to flow from channel 27 into channels 18 and 45 but preventing liquid from flowing in the opposite direction.

Tension control valve 20 has its mechanism arranged within a casing 55 having formed therein a bore 56 which communicates at its lower end with a branch of pressure channel 18 and at a point intermediate its ends with a drain channel 57 which discharges into reservoir 24. Communication between channels 18 and 57 is controlled by a valve member 58 which is closely fitted in bore 56 and urged downward by yieldable means such as a spring or by fluid pressure, so that the liquid discharged by pumps 16 and 17 in excess of the liquid consumed by motor 10 will flow through bore 56 and channel 57 into reservoir 24, and the flow through bore 56 will be resisted by valve member 58 which thereby causes pumps 16 and 17 to deliver liquid to motor 10 at a pressure proportional to the force exerted upon valve member 58 by the yieldable means.

In order that valve 20 may cause variations in the pressure of the liquid delivered to motor 10 to thereby enable motor 10 to exert a greater torque during acceleration of the winder and/or to vary the tension on the paper in response to variations in the speed thereof or to variations in the diameter of roll 3, valve member 58 is provided with a stem 59 having a plurality of pistons arranged thereon and casing 55 has a plurality of separate cylinders fitted therein so that the valve may be readily assembled.

As shown, valve stem 59 has two pistons 60 and 61 fixed thereon and fitted, respectively, in two cylinders 62 and 63 which are closely fitted in casing 55 and rigidly secured therein as by cylinder 63 being threaded into casing 55. Valve member 58 is continuously urged downward by a helical compression spring 64 arranged in the upper part of cylinder 63 between the upper face of piston 61 and a spring retainer 65 the position of which is determined by an adjusting screw 66 threaded through the upper head of cylinder 63. Turning screw 66 will vary the tension of spring 64 and thereby vary the force required to lift valve member 58 with a resultant variation in the pressure of the liquid delivered to motor 10. Therefore, since the tension of paper 2 is determined by the torque of motor 10 and since the torque of motor 10 is determined by the pressure in channel 18, turning screw 66 will vary the tension of paper 2.

In order to increase the torque of motor 10 during acceleration of the winder, cylinder 63 is connected at a point below piston 61 with drain channel 67 and at a point above piston 61 to a channel 68 through which gear pump liquid is supplied to cylinder 63 under the control of an acceleration valve 69 which is fitted in a stationary valve casing 70 and has its stem connected to suitable operating means such as a lever 71.

Valve casing 70 has both ends of its bore connected to drain channel 57 and it has two annular grooves or ports 72 and 73 formed in the wall of its bore and connected to gear pump supply channel 25 and channel 68 respectively. When valve 69 is in the position shown in Fig. 1, cylinder 63 is open to drain channel 57 so that piston 61 is not subjected to pressure. When valve 69 is shifted to the position shown in Fig. 3, liquid from gear pump 23 may flow through channel 25, valve casing 70 and channel 68 to cylinder 63 and urge piston 61 and valve member 58 downward.

In order to prevent the pressure in gear pump

supply channel 25 from dropping when valve 69 is shifted to the position shown in Fig. 3, channel 68 has inserted therein a small capacity choke 74 which permits liquid to flow through channel 68 at only a very slow rate. Also, in order to limit the force exerted upon piston 61 by the gear pump liquid, a relief valve 75 has its inlet connected to channel 68 at a point between choke 74 and cylinder 63 and its outlet connected to drain channel 57 by a channel 76.

The arrangement is such that, when acceleration valve 69 is shifted to the position shown in Fig. 3, liquid will flow at a very limited rate through choke 74 which will prevent the pressure in channel 25 from dropping, pressure will be created in the upper end of cylinder 63 and then liquid will flow through relief valve 75 and channels 76 and 57 into reservoir 24, and the liquid in the upper end of cylinder 63 will exert upon piston 61 a force proportional to the resistance of relief valve 75.

The force exerted by the liquid on piston 61 supplements the force exerted by spring 64, thereby causing the pressure in channel 18 to increase enough to enable motor 10 to have sufficient additional torque to accelerate the winder.

Cylinder 62 has its upper end connected by a channel 77 to channel 43 and its lower end connected by a channel 78 to channel 45 so that, when throttle valve 44 is adjusted to cause a drop in pressure thereacross, opposite faces of piston 60 will be subjected to the pressures prevailing at opposite sides of throttle valve 44 whereby a variation in speed will cause a variation in the downward force exerted upon valve member 58 with a resultant variation in the tension of paper 2 as will presently be explained.

When control valve 33 is in the position shown in Fig. 2 and the drive is in operation, pumps 16 and 17 will deliver liquid to motor 10 and cause it to rotate shaft 1 to wind paper 2 thereon as fast as it is delivered by machine 4 and, disregarding for the moment the very small volume which passes through the friction compensation pump to be presently described, all of the liquid discharged by motor 10 will flow through channel 42, valve casing 34, channel 43, valve 44 and channel 45 to pump 17 so that motor 10 cannot discharge liquid any faster than it can be consumed by pump 17 which is driven in unison with machine 4 so that the rate at which motor 10 discharges liquid is proportional to the speed of paper 2.

The liquid discharged by pumps 16 and 17 will tend to drive motor 10 at a speed in excess of the speed required to wind paper 2 upon shaft 1 as fast as it is delivered by machine 4 but motor 10 cannot wind up paper 2 any faster than it is delivered so that the speed of motor 10 is determined by the speed of paper 2 and the liquid discharged by pumps 16 and 17 in excess of motor requirements is exhausted through tension control valve 20 the resistance of which determines the pressure in channel 18 and consequently determines the torque of motor 10 and the tension of paper 2.

In order to maintain the tension on paper 2 constant, the torque of motor 10 must increase and the speed of motor 10 must decrease as roll 3 increases in diameter. Since the speed of a hydraulic motor is proportional to its displacement and to the rate at which it discharges liquid, and since the discharge of motor 10 is proportional to the speed of pump 17 and to the speed of paper 2 as previously explained,

varying the displacement of motor 10 will also vary the speed of motor 10. Also, since the torque of a hydraulic motor is proportional to its displacement and to the drop in pressure thereacross and since liquid is supplied to motor 10 at a pressure which remains constant at any particular setting of tension control valve 20, varying the displacement of motor 10 will vary the motor torque.

10. Therefore, a variation in motor torque at any given motor displacement will cause a corresponding variation in the pressure in the return side of the circuit, and these pressure variations are utilized for adjusting the displacement of 15 motor 10. This is accomplished by connecting stroke control cylinder 15 to the return side of the circuit so that the pressure prevailing in the return side of the circuit acts upon piston 14 and tends to cause it to move slide block 11 toward 20 the right against the resistance offered by piston 12 which is at all times subjected to gear pump pressure through channel 25.

In order that cylinder 15 may not be subjected to high pressure when motor 10 is discharging through brake valve 46, it is connected to the return side of the circuit at a point beyond control valve 33 as by being connected to return channel 45 through a channel 85 which is also connected through a low pressure relief valve 30 86 to low pressure channel 27. Relief valve 86 protects cylinder 15 from excessive pressures and provides a path for the liquid discharged by motor 10 when motor 10 is being operated at a slow speed by liquid supplied only by pump 16 as will presently be explained.

The arrangement is such that, when the drive is in operation, an increase in the diameter of roll 3 due to paper 2 being wound thereon will cause the speed of motor 10 to lag and the pressure in channels 45 and 85 and in cylinder 15 will drop and permit piston 12 to shift slide block 11 toward the left to increase the displacement of motor 10 and thereby simultaneously increase the torque and decrease the speed of motor 10.

45. In the prior winder drives, the displacement varying member was shifted in response to pressure variations in the pressure side of the circuit but variation in the slip of the drive caused considerable variation in motor torque with resultant variation in the tension on the paper. By shifting the displacement varying member in response to pressure variation in the return side of the circuit in which there is but little slip due to the low pressure therein, errors in tension 55 due to slip are practically eliminated. In fact, tests show that such errors are reduced about 89%.

Another important feature of the present invention is the compensation for the friction in the winding machine and in the hydraulic motor. 60 Tests indicate that this friction is approximately constant at any given tension. When the roll is small, the friction is high because of the high speed of the winder roll. When the roll gets 65 large, the friction remains equally high because, in maintaining the proper tension, the torque and the bearing loads increase at substantially the same rate that the speed of the roll decreases.

70. Consequently, at any given tension, the motor torque required to overcome the friction of the motor and the winder will remain constant while the motor torque required to rotate shaft 1 and maintain the desired tension on paper 2 will 75 increase as roll 3 increases in diameter. There-

fore, if no means were provided for compensating for friction, the displacement of motor 10 would be initially adjusted in the above described manner until motor 10 was exerting just sufficient torque to overcome the friction and to exert the 5 desired tension on paper 2 and then the displacement and torque will be gradually increased in response to roll 3 increasing in diameter but the torque would not increase at the same rate that roll 3 increased in diameter.

10. It therefore follows that, in order to maintain the tension on paper 2 at the desired value, slide block 11 of motor 10 must be shifted by an amount which varies in accordance with variations in the diameter of roll 3 as explained above 15 and, in addition, it must be shifted by an amount which remains constant at any given tension on paper 2. This is accomplished by extracting a given small volume of liquid from the return side of the circuit during each revolution of motor 10.

As shown, a small pump 87 is driven in unison with motor 10, as by being connected to the shaft thereof by a suitable drive 88, and it has its intake connected to the return side of the 25 circuit and its outlet connected to low pressure channel 27. In order to protect pump 87 from high pressure when motor 10 exhausts through brake valve 46, it is connected to the return side of the circuit at a point beyond control valve 30 33 as by having its intake connected to channel 43 by a channel 89.

When the drive is in operation, pump 87 extracts liquid from the return side of the circuit and thereby permits piston 12 to move slide block 35 11 toward the left beyond the point to which it is moved in the above described manner in response to pressure variations in the return side of the circuit. The distance that slide block 11 is moved in response to operation of pump 87 40 is just enough to enable motor 10 to have just the torque necessary to overcome its own friction and the friction of the winder. This increase in motor displacement causes the liquid discharged by motor 10 to increase by an amount 45 which is exactly equal to the volume extracted by pump 87 so that pump 87 causes no further increase in motor displacement but simply maintains the displacement a given amount in excess of the displacement produced in the above 50 described manner in response to variations in the pressure in the return side of the circuit.

By thus compensating for friction, the errors in the tension on the paper due to friction have been practically eliminated. In fact, tests show that such errors have been reduced 87%.

Pump 87 has been shown as being of the variable displacement type so that it may be adjusted when the tension on paper 2 is changed but, where a particular drive is intended to always maintain approximately the same tension on the paper, a constant displacement pump is used in actual practice for the reason that it is so much cheaper.

Operation

65. Assuming that paper 2 has been attached to shaft 1, that lever 8 and valves 33 and 69 are in the positions shown in Fig. 1, that throttle valve 44 is fully open so that it offers no resistance to 70 the flow of liquid therethrough and that pumps 16 and 23 and the prime mover which drives transmission 7 are running, machine 4 and pump 17 will be idle, pump 16 will circulate liquid from low pressure channel 27 through channels 18 and 71

41 and valve casing 34 back into channel 27, gear pump 23 will draw liquid from reservoir 24 and discharge it through channel 25, gear pump relief valve 26, channel 27, low pressure relief valve 28, channel 29 into reservoir 24, the pressure created by gear pump 23 due to the resistance of relief valve 26 will extend through channel 25 to cylinder 13 and cause piston 12 to move slide block 11 toward the left to increase the displacement of motor 10 to maximum, and slide block 11 will cause piston 14 to expel liquid from cylinder 15 through channels 85 and 45, valve 44, channel 43, valve casing 34, low pressure channel 27, relief valve 28 and channel 29 into reservoir 24.

15 To start the machine, lever 8 is shifted from the position shown in full lines to the position shown in dotted lines. When it has been shifted approximately half way between these two positions, it will have moved valve 33 approximately 20 half way from the position shown in Fig. 1 to the position shown in Fig. 2 which is far enough to partly uncover port 39 and to block communication between ports 37 and 36 but transmission 7 will still be inoperative so that machine 4 and pump 17 will not be started until lever 8 is moved 25 farther toward the position shown in dotted lines.

Blocking communication between ports 37 and 36 stops pump 16 from discharging into low pressure channel 27 and causes it to deliver liquid through channel 18 to motor 10 to energize it. Motor 10 being at full stroke, it has ample torque to enable it to overcome its own friction and inertia and the friction and inertia of the 30 winder so that it can readily rotate shaft 1 to take the slack out of paper 2.

As soon as motor 10 starts, the liquid discharged by it will flow through channel 42, valve casing 34, channel 43, valve 44 and channels 45 and 85 to cylinder 15 and cause piston 14 to shift slide block 11 toward the right and thereby reduce the displacement of motor 10 to a predetermined minimum and then all of the liquid discharged by motor 10 will be exhausted through relief valve 86 into low pressure channel 27 except for 40 a small volume which pump 81 extracts from channel 43 and discharges into channel 27, the movement of slide block 11 toward the right being limited in the usual manner so that at its minimum displacement motor 10 will have sufficient torque to rotate shaft 1.

If there is a considerable amount of slack in paper 2, lever 8 is moved alternately in opposite directions to alternately start and stop motor 10 so that it will not be driving shaft 1 at a high 55 speed at the instant that the slack is taken up. Ordinarily however, the amount of slack in paper 2 is so small that it is taken up during gradual movement of lever 8 from the point at which it causes motor 10 to be energized to the point at 60 which it causes transmission 7 to transmit motion from the prime mover to drive 6.

Moving lever 8 to the position shown in dotted lines causes valve 33 to be moved to the position shown in Fig. 2 and also causes machine 4 and pump 17 to be driven at slow speeds, thereby causing machine 4 to deliver paper at a slow speed and pump 17 to discharge liquid at a rate proportional to the speed of paper 2.

Pump 17 will draw its supply of liquid from 70 channel 45 and thereby cause the pressure therein and in channel 85 and in cylinder 15 to drop and permit relief valve 86 to close so that thereafter all the liquid discharged by motor 10 must pass through pump 17 and the displacement of motor 10 will be automatically adjusted in re-

sponse to variations in the pressure in the return side of the circuit as previously explained.

The liquid discharged by pumps 16 and 17 will flow through channel 18 to motor 10 and cause it to drive shaft 1 to wind paper 2 thereon. 5 Due to pump 16, the liquid tends to drive motor 10 faster than the rate required to wind up paper 2 as fast as it is delivered by machine 4, thereby causing the pressure to rise and the excess liquid to be discharged through tension control valve 10 20 the resistance of which determines the pressure of the liquid in channel 18 and the torque of motor 10.

Pump 81 is driven in unison with motor 10 and extracts a given amount of liquid from the return side of the circuit during each revolution of motor 10 to increase motor displacement by the amount necessary to enable motor 10 to have the required amount of torque to cause it to exert the desired tension on paper 2. 20

Machine 4 may be accelerated to a desired high speed by adjusting transmission 7 or the prime mover that drives it, thereby simultaneously accelerating pump 17 for the reason that it is driven in unison with machine 4 and also causing motor 25 10 to accelerate and wind paper 2 onto roll 3 as fast as it is delivered by machine 4 for the reason that pump 17 regulates the stroke of motor 10 by metering the discharge therefrom.

Simultaneously with the adjustment of transmission 7 or the prime mover to accelerate machine 4, valve 69 is shifted to the position shown in Fig. 3 to cause in the previously described manner an increase in the resistance of valve 20 and in the pressure in channel 18 so that the 35 torque of motor 10 is increased sufficiently to enable it to accelerate shaft 1 and to maintain the desired tension on paper 2. As soon as acceleration ceases, valve 69 is returned to the position shown in Fig. 1 and then the pressure in channel 18 and the tension on paper 2 will be determined by spring 64 the tension of which may be adjusted by turning screw 66. 40

As paper 2 accumulates on shaft 1, the torque of motor 10 must gradually increase and the speed of motor 10 must gradually decrease in order to maintain a uniform tension on paper 2 for the reason that paper 2 is being delivered at a uniform linear speed while roll 3 increases in diameter and its rotary speed decreases relative 45 to its peripheral speed. 50

Since the pressure in channel 18 is constant at any given adjustment of tension control valve 20 and since pump 17 is driven at a speed proportional to the linear speed of paper 2 and meters the outflow from motor 10, the decrease in rotary speed will cause the pressure in the return side of the circuit to drop and permit gear pump pressure acting upon piston 12 to move slide block 11 toward the left to increase the displacement of motor 10 with a resultant increase in the torque thereof. Since the increase in roll diameter causes a corresponding decrease in speed, the volumetric output of motor 10 remains unchanged so that slide block 11 is moved toward the left at a rate proportional to the rate at which roll 3 increases in diameter and thereby causes the torque of motor 10 to increase and the speed of motor 10 to decrease at the same rate that roll 3 increases in diameter. Motor 10 is thus enabled to maintain a 60 substantially uniform tension upon paper 2. 65

The drive is normally stopped by gradually decelerating the prime mover and adjusting transmission 7. If it is desired to decelerate the 70 75

drive at a rapid rate, the desired tension may be maintained on the paper by reducing the torque of motor 10 during rapid deceleration as by the means to be presently described.

5 If the paper should break or other emergency arise, lever 8 is shifted from the position shown in dotted lines to the position shown in full lines, thereby stopping the flow of power to machine 4 and simultaneously shifting control valve 33 10 to the position shown in Fig. 1 so that port 39 is blocked and port 37 is opened to port 36.

Machine 4 will coast to a stop so that pump 17 will continue to deliver liquid until machine 4 comes to rest and pump 16 will deliver liquid 15 continuously but opening port 37 to port 36 short circuits both pumps and prevents motor 10 from being energized.

Motor 10 will continue to run due to its inertia and the inertia of roll 3 but blocking port 39 20 causes it to discharge through brake valve 46 which resists the discharge of liquid therethrough and thereby decelerates motor 10 quickly and smoothly to a complete stop.

It is sometimes desirable to vary the tension 25 on paper 2 in response to a variation in speed. For example, it has been found necessary under certain conditions to increase the torque of the winder motor as the speed increases in order to obtain a satisfactory roll of paper due, possibly, to too much clearance in the winding shaft bearings or to curvature of the shaft.

Since pump 17 is driven in unison with machine 4 and meters the outflow from motor 10 so that the velocity of the liquid in the return 35 side of the circuit is proportional to the linear speed of paper 2, the torque of motor 10 may be varied in response to a variation in speed by providing a restriction in the return side of the circuit and causing the resistance of tension control valve 20 to be varied in response to a variation 40 in the drop in pressure across the restriction.

As shown, valve 44 when partly closed will 45 cause a slight drop in pressure thereacross, the pressure in channel 43 will extend through channel 71 to the upper end of cylinder 62 and act upon the upper face of piston 60, and the pressure in channel 45 will extend through channel 78 to the lower end of cylinder 62 and act upon 50 the lower face of piston 60 so that the downward force exerted upon valve member 58 by spring 64 is augmented by an additional force equal to the difference between the forces exerted by the liquid 55 upon opposite faces of piston 60.

An increase in speed will cause the velocity of the liquid in the return side of the circuit to increase and increase the drop in pressure across valve 44 with a resultant increase in the downward force exerted upon valve 58, thereby causing the pressure in channel 18 to increase and enable motor 10 to exert a greater torque.

If it should be desired to decrease the torque 65 of motor 10 as the speed increases, the connections of channels 71 and 78 may be reversed so that the lower face of piston 60 is subjected to the pressure in channel 43 and the upper face of piston 60 is subjected to the pressure in channel 45.

Fig. 4

The motor torque may be varied at a substantially constant rate, a progressively depressing rate, a progressively increasing rate or a combination of such rates by varying the shape of the 75

orifice which provides the restriction in the return side of the circuit.

This figure shows a valve 44^a connected into the return side of the circuit instead of the throttle valve 44 shown in Fig. 1. Valve 44^a has a valve member 92 fitted in its casing 93 and urged downward against a stop screw 94 by a spring 95 the tension of which is adjusted by means of an adjusting screw 96. An inlet port 97 is formed in the lower part of casing 93 and connected to channel 43, and an annular outlet port 98 is formed in casing 93 around valve member 92 and connected to channel 45. Communication between ports 97 and 98 is controlled by valve member 92 which has one or more slots 99 15 formed in the lower part thereof.

When the drive is in operation, the liquid discharged by motor 10 (Fig. 1) will flow through channel 42, valve casing 34 and channel 43 to inlet 97 (Fig. 4) and raise valve member 92 20 against the resistance of spring 95 and then the liquid will flow through slots 99 to outlet 98 and then through channel 45 to pump 17.

Valve member 92 will throttle the flow from inlet 97 to outlet 98 and thereby cause a drop in 25 pressure between channels 43 and 45. The pressure in channel 43 will extend through channel 71 to the upper end of cylinder 62 in tension control valve 20 (Fig. 1) and the pressure in channel 45 will extend through channel 78 to the lower end of cylinder 62 so that valve member 58 is urged downward by an additional force proportional to the difference between the pressures in channels 43 and 45 as previously explained.

As the flow in the return side of the circuit 35 increases in response to an increase in the speed of the machine, valve member 92 will be raised higher to permit the passage through valve 44^a at a faster rate and the resistance it offers to the increased flow will increase and thereby increase the drop in pressure across valve 44^a with a resultant increase in the pressure in channel 18 and the torque of motor 10 at a rate determined by the shape of slots 99.

If slots 99 are shaped approximately as shown, 45 the torque of motor 10 will be uniformly increased as the speed increases, but they may be shaped to cause the torque to increase at almost any desired rate either uniform or nonuniform.

Fig. 5

50

It is often necessary to gradually vary the tension on the paper in response to the roll increasing in diameter in order to produce a roll the density of which gradually varies from the 55 inside to the outside thereof. One reason for this requirement is that, under certain conditions, the moisture content of the paper changes after the roll is wound and thereby changes the length of the paper so that, by gradually varying the density of the roll during the winding thereof, the roll is of uniform density when ready to use.

Since slide block 11 is gradually moved toward the left in response to roll 3 gradually increasing 65 in diameter, a gradual variation in tension may be obtained by increasing the resistance of tension control valve 20 in response to movement of slide block 11. This may be accomplished by varying the resistance of tension control valve 70 20 in response to variation in the drop in pressure across a spring loaded resistance valve the resistance of which is varied in response to movement of slide block 11.

The drive shown in Fig. 5 is exactly the same 75

as the drive shown in Fig. 1 except that the liquid discharged by motor 10 flows through a low pressure resistance valve 102 instead of through throttle valve 44. This requires a slight rearrangement of certain channels which have been indicated by the same reference numerals with the exponent "a" added thereto.

In order to simplify the view, resistance valve 102 has been shown attached to stroke control cylinder 15 on motor 10 with its adjusting stem extending through the head thereof into contact with piston 14 so that movement of slide block 11 toward the left will compress the resistance valve spring and thereby increase the resistance of valve 102 but, since this arrangement would require a gland around the adjusting stem, the resistance valve is ordinarily attached to the motor casing with its adjusting stem extending therethrough into contact with slide block 11.

Resistance valve 102 has been shown as being nonadjustable but in practice an adjustable valve is employed such as by providing means for varying the length of the adjusting stem or providing an adjustable mechanical linkage between the adjusting stem and a pin which is fastened to the slide block and extends through the motor casing.

The inlet of resistance valve 102 is connected to port 38 in control valve casing 34 by a channel 43^a which corresponds with channel 43 and has channel 89 connected thereto, and the outlet of resistance valve 102 is connected to the intake of pump 17 by a channel 45^a which corresponds with channel 45. Channels 43^a and 45^a are connected, respectively, to the upper and lower ends of cylinder 62 in tension control valve 20 by two channels 77^a and 78^a which correspond to channels 77 and 78. Since the other parts are exactly the same as in the drive shown in Fig. 1, they have been indicated by the same reference numerals and no further description thereof will be given.

The arrangement is such that, when the drive is in operation, all of the liquid discharged by motor 10 (except for the very small volume that passes through pump 87) flows through channel 42, valve casing 34, channel 43^a, resistance valve 102 and channel 45^a to the intake of pump 17. Resistance valve 102 will resist the flow of liquid therethrough and cause a drop in pressure between channel 43^a and channel 45^a, the pressure in channel 43^a will extend through channel 77^a to the upper end of cylinder 62 and the pressure in channel 45^a will extend through channel 78^a to the lower end of cylinder 62 so that piston 60 is urged downward by a force proportional to the drop in pressure across resistance valve 102, thereby increasing the resistance of tension control valve 20 above the resistance determined by the tension of spring 64.

When slide block 11 gradually moves toward the left to gradually increase the displacement of motor 10 in response to roll 3 gradually increasing in diameter as previously explained, it will gradually increase the resistance of resistance valve 102 and thereby cause the drop in pressure across valve 102 to gradually increase so that the force exerted upon piston 60 is gradually increased. Gradually increasing this force will gradually increase the resistance of valve 20 and the pressure in channel 18 so that the torque of motor 10 gradually increases and thereby causes the tension on paper 2 to gradually increase as roll 3 increases in diameter.

If it is desired to gradually decrease the ten-

sion on paper 2 as roll 3 increases in diameter, it is simply necessary to reduce the resistance of resistance valve 102 in response to roll 3 increasing in diameter. This may be accomplished by arranging resistance valve 102 on the other side of motor 10, as indicated by the resistance valve shown in Fig. 6, so that its resistance will be reduced as slide block 11 moves toward the left.

10

Fig. 6

Instead of varying the tension on paper 2 as roll 3 increases in diameter by varying the resistance of tension control valve 20 in response to variation in the drop in pressure across a resistance valve connected into the return pipe of the hydraulic circuit as shown in Fig. 5, the same result may be achieved by varying the resistance of valve 20 in response to variation in the drop in pressure across a resistance valve 20 through which liquid flows from a source other than the hydraulic circuit, such as from gear pump 23.

As shown in Fig. 6, a low pressure resistance valve 103 is attached to stroke control cylinder 13 on motor 10 with its adjusting stem extending through the head thereof into contact with piston 12 so that movement of slide block 11 toward the left will permit the resistance valve spring to expand and thereby decrease the resistance of valve 103 but, since this arrangement would require a gland around the adjusting stem, the resistance valve is ordinarily attached to the motor casing with its adjusting stem extending therethrough into contact with slide block 11.

Resistance valve 103 has its inlet connected to one end of a channel 104 having the other end thereof connected to gear pump supply channel 25 through a choke 105 which limits the flow of liquid from channel 25 into channel 105 to a very slow rate so that the pressure in channel 104 may be determined by the resistance of resistance valve 103.

The outlet of resistance valve 103 is connected to the lower end of cylinder 62 in tension control valve 20 by a channel 78^b which is also connected by channel 106 to drain channel 57, so that the pressure at the outlet of resistance valve 103 and in the lower end of cylinder 62 is substantially zero, and channel 104 is connected to the upper end of cylinder 62 by a channel 77^b so that the upper face of piston 60 is subjected to the pressure prevailing in channel 104.

Except for the addition of resistance valve 103, choke 105 and channels 104 and 106, and connecting the upper and lower ends of cylinder 62 to the inlet and outlet of resistance valve 103 by channels 77^b and 78^b instead of to channels 43 and 45 by channels 77 and 78, the drive is exactly the same as the drive shown in Fig. 1, it being understood that either throttle valve 44 is fully opened or it is omitted and channel 43 connected directly to channel 46. Consequently, only a part of the drive has been illustrated and no further description thereof will be given, such parts as are shown being indicated by the same reference numerals that are employed in Fig. 1 to indicate corresponding parts.

When the drive is in operation, liquid supplied by gear pump 23 to channel 25 will flow at a limited rate through choke 105, channel 104, resistance valve 103 and channels 78^b, 106 and 57 into reservoir 24. Resistance valve 103 will resist the flow of liquid therethrough and

75

thereby cause pressure to rise and extend through channel 77^b to the upper end of cylinder 62 and act upon the upper face of piston 60.

Since the lower end of cylinder 62 is open to drain, piston 60 will be urged downward by a force proportional to the resistance of valve 103 and thereby increase the resistance of tension control valve 20 above the resistance determined by the tension of spring 64 so that the pressure in channel 18 is increased to thereby enable motor 10 to exert a greater torque and maintain upon paper 2 a tension greater than the tension determined by spring 64.

When slide block 11 gradually moves toward the left to gradually increase the displacement of motor 10 in response to roll 3 gradually increasing in diameter as previously explained, it will gradually reduce the resistance of resistance valve 103 and thereby cause the pressure in channels 104 and 77^b and in the upper end of cylinder 62 to be gradually reduced so that the force exerted upon piston 60 is gradually reduced. Gradually reducing this force will gradually reduce the resistance of valve 20 and the pressure in channel 18 so that the torque of motor 10 is gradually reduced and thereby causes the tension on paper 2 to be gradually reduced as roll 3 increases in diameter.

If it is desired to gradually increase the tension on paper 2 as roll 3 increases in diameter, it is simply necessary to increase the resistance of resistance valve 103 in response to roll 3 increasing in diameter. This may be accomplished by arranging resistance valve 103 on the other side of motor 10, as shown in Fig. 5 by the position of resistance valve 102, so that its resistance will be increased as slide block 11 moves toward the left.

Fig. 7

40 The drive shown in this figure differs from the drive shown in Fig. 6 only in that it is provided with a different tension control valve and the connections thereto are somewhat different.

45 As shown, the drive is provided with a tension control valve 20^a which is substantially the same as tension control valve 20 except that it has a third piston 110 fixed upon its stem 59 between pistons 60 and 61 and fitted in a cylinder 111 arranged in casing 55 between cylinder 62 and a cylinder 63^a which is the same as cylinder 63 except that it is shorter.

50 Cylinder 62 has channels 77 and 78 connected to the upper and lower ends thereof, respectively, and cylinder 63^a has channel 68 connected to the upper end thereof. The upper end of cylinder 111 is connected by a channel 77^b to a channel 104 which has one of its ends connected through a choke 105 to gear pump supply channel 25 and its other end connected to the inlet of a resistance valve 103 carried by cylinder 13. The outlet of resistance valve 103 is connected to one end of a channel 78^b the other end of which is connected directly to the lower end of cylinder 111 and through a channel 108^a to drain channel 57.

55 The arrangement is such that, when the drive is in operation, opposite faces of piston 60 are subjected to the pressures prevailing upon opposite sides of throttle valve 44 (Fig. 1) or valve 44^a (Fig. 4) so that the resistance of tension control valve 20^a is varied in response to a variation in the drop in pressure across valve 44 or 44^a due to a variation in speed as previously explained, liquid from gear pump 23 (Fig. 1) will

flow through channel 25, choke 105, channel 104, resistance valve 103 and channels 78^b and 108^a into drain channel 57, pressure will extend from channel 104 through channel 77^b to the upper end of cylinder 111 and act upon piston 5 110 so that the resistance of tension control valve 20 is varied in response to variation in the drop in pressure across resistance valve 103, and as slide block 11 moves toward the left due to roll 3 increasing in diameter it reduces the 10 resistance of resistance valve 103 to thereby cause motor 10 to gradually vary the tension on paper 2 in response to roll 3 gradually increasing in diameter as previously explained in connection with the description of the drive shown 15 in Fig. 6.

20 Since the other parts of the drive are exactly the same as the corresponding parts of the drive shown in Fig. 6, like parts have been indicated by like reference numerals and no further 20 description thereof will be given, it being deemed sufficient to state that, with the drive constructed as shown, the tension on paper 2 will be increased in response to an increase in speed and decreased in response to roll 3 increasing in diameter, that the tension on paper 2 may be decreased in response to an increase in speed by simply interchanging the connections of channels 77 and 78 to cylinder 62 or to channels 43 and 45, and that the tension on paper 2 may be 25 increased in response to roll 3 increasing in diameter by simply attaching resistance valve 103 to the other side of motor 10 as previously explained.

Fig. 8

35

It has previously been explained that motor 10 winds paper 2 upon the shaft 1 as fast as it is delivered by machine 4 so that the speed of motor 10 is determined by the speed of paper 40 2, that the pressure of the liquid which energizes motor 10 is constant at any given adjustment of valve 20 so that motor 10 exerts just sufficient torque to rotate shaft 1 and to maintain a given tension upon paper 2.

45 Therefore, since the torque required to accelerate a rotating mass is greater than the torque required to keep it rotating, motor 10 must be enabled to exert a greater torque during acceleration in order to maintain the desired 50 tension upon paper 2. In fact, it has been found that the paper will sometimes run ahead of the winding roll unless means are provided for enabling the motor to exert a greater torque during 55 acceleration.

55 Shifting acceleration valve 69 from the position shown in Fig. 1 to the position shown in Fig. 2 at the beginning of acceleration enables motor 10 to exert a greater torque during acceleration but the motor torque is increased 60 by a definite amount while the operator may accelerate paper 2 at one rate at one time and at a different rate at another time so that there is no assurance that shifting valve 69 will enable motor 10 to have the correct torque to exert the desired tension on the paper during acceleration.

65 In order that the motor torque may be automatically increased in response to the paper 70 being accelerated, manually operable acceleration valve 69-70 and the connections thereto may be omitted as shown in Fig. 9 and an automatic acceleration valve 120 may be connected into the return side of the circuit to increase 75

the resistance of tension control valve 20 during acceleration of the paper.

As shown in Fig. 8, acceleration valve 120 has its mechanism arranged within a casing 121 having a bore 122 and a counterbore 123 formed therein concentric with each other. Bore 122 is connected at its lower end to channel 43 and it has an annular groove or port 124 formed in its wall intermediate its ends and connected by a channel 125 to channel 45.

Communication between channel 43 and port 124 is controlled by a valve member 126 which is closely fitted in bore 122 and provided at its lower end with one or more slots so that gradual upward movement of valve member 126 will gradually increase the opening between the lower end of bore 122 and port 124.

Valve member 126 is urged downward by a substantially constant force such, for example, that will require a pressure of only about 1 pound per square inch in channel 43 to raise valve member 126 to open channel 43 to channel 45. While valve member 126 may be urged downward by a spring which is so soft that its resistance is not materially increased by compressing it enough to permit valve member 126 to open channel 43 to channel 45, valve member 46 has been shown provided at its upper end with a weight 127 which is arranged in counterbore 123.

In order to delay the opening of valve 120, counterbore 123 is entirely closed except for a passage 128 which communicates with channel 125 and has a needle valve 129 arranged therein to limit the rate at which liquid may flow therethrough. Valve 120 has been shown arranged above control valve 33 in order to simplify the drawings but in practice it is arranged below the level of the liquid in a reservoir, such as reservoir 24, so that counterbore 123 is filled with liquid at all times.

During normal operation of the drive, valve 120 will cause a slight drop in pressure between channels 43 and 45, the pressure in channel 43 will extend through channel 71 to the upper end of cylinder 62 in tension control valve 20 (Fig. 1), and the pressure in channel 45 will extend through channel 78 to the lower end of cylinder 62 so that piston 60 is urged downward by a force proportional to the drop in pressure across valve 120, thereby increasing the resistance of tension control valve 20 above the resistance determined by spring 64 the tension of which is adjusted to compensate for the force exerted upon piston 60.

When paper 2 is accelerated, the flow in the circuit will increase as previously explained. Since the drop in pressure across an orifice varies nearly in proportion to the square of the velocity of the liquid passing therethrough, an increase in the rate of flow will cause a considerable increase in the pressure in channel 43 and this increase in pressure will raise valve member 126 which will expel liquid from counterbore 123 but the escape of liquid from counterbore 123 is retarded by needle valve 129 so that valve member 126 must rise very slowly, thereby causing a considerable increase in the pressure in channels 43 and 71 and the upper end of cylinder 62. Increasing the pressure in the upper end of cylinder 62 will increase the downward force exerted upon piston 60 and consequently increase the resistance of tension control valve 20 so that the pressure in chan-

nel 18 is increased to thereby enable motor 10 to exert sufficient additional torque to accelerate the winder and to maintain the desired tension on paper 2.

Valve member 126 will continue to slowly move upward during acceleration but the flow will continue to increase so that valve 120 continues to cause a considerable drop in pressure thereacross as long as acceleration continues but, when acceleration ceases, valve member 126 will have been raised high enough to reduce the drop in pressure across valve 120 to normal so that the torque of motor 10 is reduced to normal.

When machine 4 is decelerated without shifting control valve 33 to the position shown in Fig. 1 so as to short circuit pumps 16 and 17 and to apply a brake load to motor 10 as previously explained, the pull of the paper will decelerate motor 10, the pressure in channel 18 will be maintained at the value determined by tension control valve 20 so that motor 10 continues to exert the same pull on the paper, and the inertia of the rotating masses will increase the pull on the paper so that the tension becomes excessive if deceleration is rapid.

Therefore, in order to maintain the tension on the paper at approximately the desired value, the motor torque must be decreased during rapid deceleration. This may be accomplished by increasing the effect of valve 120 on tension control valve 20 and then reducing the tension of spring 64 to maintain the resistance of tension control valve 20 at the correct value to enable motor 10 to maintain the desired tension on the paper during normal operation.

The effect of valve 120 on valve 20 may be increased by increasing the area of piston 60, so that a small drop in pressure across valve 120 will cause a considerable increase in the resistance of valve 20, or by increasing the drop in pressure across valve 120 as by using a larger weight 127 or, if valve member 126 is urged downward by a spring, by increasing the tension of the spring.

Then when motor 10 is decelerated, the resultant decrease in the velocity of the liquid flowing through valve 120 will cause a decrease in the drop in pressure across valve 120 and thereby reduce the resistance of tension control valve 20 so that the torque of motor 10 is correspondingly decreased. By properly proportioning and adjusting the parts, the decrease in motor torque may be made to offset the pull exerted upon the paper due to the inertia of the rotating masses, thereby maintaining the tension on the paper at approximately the desired value.

Figs. 9 to 13

Instead of enabling the winder motor to exert additional torque during acceleration by increasing the resistance of tension control valve 20 in response to manual operation of an acceleration valve as shown in Fig. 1 or in response to an increase in the drop in pressure across an automatic acceleration valve as shown in Fig. 8, the torque of the winder motor may be increased during acceleration and decreased during deceleration by varying the resistance of tension control valve 20 in response to operation of a mass actuated governor which is driven in unison with the winder motor.

This is accomplished by the drive shown in Fig. 9 which differs from the drive shown in

- Fig. 1 only in that the manually operated acceleration valve and the connections thereto are omitted, the drive is provided with a winder motor 10^a which is exactly the same as motor 10 except that it is provided with a mass actuated governor for tension control valve 20, and cylinder 63 in valve 20 is connected by a channel 68^a to the mass actuated governor instead of being connected by channel 68 to the manually operated acceleration valve. Since the drive is otherwise the same as the drive shown in Fig. 1, like parts have been indicated by like reference numerals and no further description thereof will be given.
- 15 Due to the mass actuated governor, the shaft 131 (Fig. 10) of motor 10^a is longer than the shaft of motor 10 and is supported in a bearing 132 carried by a special end head 133 which is attached to the motor casing 134 and closed at its inner end by plate 135 having formed therein an opening 136 through which liquid may escape from the interior of end head 133 into the interior of casing 134.
- 20 Shaft 131 extends through a two piece gland 137 which is attached to end head 133 and has a groove 138 formed therein around shaft 131, suitable packing 139 and 140 being provided to prevent the escape of liquid from groove 138 through the ends of gland 137.
- 25 Groove 138 is connected by a channel 141 to one end of a channel 142 (Fig. 9) which is connected at its other end to the outlet of a choke 143 and is connected intermediate its ends by a channel 68^a to the upper end of cylinder 63 in tension control valve 20. The inlet of choke 143 is connected to gear pump supply channel 25 so that liquid may flow from gear pump 23 through channel 25, choke 143 and channels 142 and 141 to groove 138 at a very limited rate as determined by choke 143, and the pressure created in channel 142 by the mass actuated governor to be presently described will extend through channel 68^a to the upper end of cylinder 63 and urge piston 61 downward to increase the resistance of tension control valve 20.
- 30 Shaft 131 (Fig. 10) has formed therein a passage 144 which extends radially inward from groove 138, then longitudinally of shaft 131 and then radially outward into communication with one end of a passage 145 (Fig. 11) formed in an impeller 146 which is fixed, as by means of a key 147, upon shaft 131 and has two diametrically opposed slots 148 and 149 extending inward from the periphery thereof.
- 35 The other end of passage 145 communicates with a bore 150 which is formed in impeller 146 and has one of its ends closed and its other end opening into slot 148. Bore 150 contains a valve 151 having two pistons 152 and 153 arranged upon opposite ends thereof. Piston 152 controls communication between bore 150 and slot 148 and thereby regulates the rate at which liquid may escape from bore 150 into end head 133. Piston 153 has formed therein a small groove 154 through which liquid may flow to the closed end of bore 150 and act upon piston 153 so that valve 151 is urged outward or in a direction to open bore 150 to slot 148 by the pressure prevailing in passage 145.
- 40 The outer end of valve 151 engages a lug 155 arranged in slot 148 and fixed to a fly wheel 156 which is rotatably supported concentric with shaft 131 as by means of a ball bearing 157 carried by the hub of impeller 146. The arrangement is such that fly wheel 156 is rotated solely

by the force transmitted thereto through valve 151 when impeller 146 is rotated.

In order to hold lug 155 in contact with piston 152 during normal operation of the winder motor and to decrease the motor torque during deceleration, fly wheel 156 has a lug 158 fixed thereto and extending into slot 149. Lug 158 engages a plunger 159 arranged in a bore 160 which is formed in impeller 146 and contains a spring 161 to urge plunger 159 toward lug 158, movement 10 of plunger 159 in that direction being limited by suitable shoulders formed upon plunger 159 and around the end of bore 160.

When the drive is in operation, liquid will flow from gear pump 23 (Fig. 9) through channel 25, 15 choke 143, channels 142 and 141 (Fig. 10), groove 138, passages 144 and 145 (Fig. 11) and bore 150 into end head 133 at a very limited rate as determined by choke 143. The liquid may escape from end head 133 through opening 136 into 20 motor casing 134 from which it is drained to a reservoir in the usual manner.

If it is desired to reduce the motor torque during deceleration, the several parts are so arranged that lug 155 holds piston 152 close enough 25 to the end of bore 150 to cause it to throttle the flow of liquid therefrom and thereby cause pressure to rise in channel 142 and extend through channel 68^a to cylinder 63. Since this pressure will act upon piston 61 and thereby increase the 30 resistance of tension control valve 20, the tension of spring 64 is correspondingly reduced so that the resistance of valve 20 will be just sufficient to enable motor 10^a to maintain the desired tension on the paper during normal operation. 35

When motor 10^a is started or accelerated, impeller 146 will start or accelerate as it is fixed to shaft 131 but, since flywheel 156 is rotatably supported upon the hub of impeller 146, its inertia will cause it to lag behind impeller 146 and move valve 151 into bore 150 to increase the throttling effect of piston 152 and thereby cause the pressure in the channels between bore 150 and choke 143 to rise and increase the resistance of tension control valve 20 so that motor 10^a is 45 enabled to exert a greater torque as previously explained.

The faster motor 10^a starts or accelerates the greater the force required to start or accelerate flywheel 156 so that the force transmitted from 50 impeller 146 through valve 151 to fly wheel 156 will be approximately proportional to the rate of acceleration. Since the pressure in channel 145 will increase in proportion to the increase in the force transmitted through valve 151, the resistance of tension control valve 20 and consequently the torque of motor 10^a will increase approximately in proportion to the rate of acceleration so that motor 10^a is able to maintain the desired tension on paper 2 regardless of the rate at 60 which it is accelerated.

When motor 10^a is decelerated, impeller 146 will be decelerated with it due to being fastened to shaft 131 but flywheel 156 must be decelerated through the contact of lug 158 with plunger 159. 65 The energy stored in flywheel 156 will cause lug 158 to move plunger 159 into bore 160 against the resistance of spring 161 and thereby cause lug 155 to move away from the end of bore 150 and permit the liquid in the inner end of bore 70 150 to move valve 151 outward to reduce the throttling effect of piston 152 so that the pressure in the channels between bore 150 and choke 143 is reduced. This reduction in pressure will cause a corresponding reduction in the resistance 75

5 of tension control valve 20 and thereby reduce the torque of motor 10^a by an amount sufficient to compensate for the inertia of the rotating masses so that the tension on the paper is maintained at approximately the desired value as previously explained.

10 Since the drive otherwise operates in exactly the same manner as the drive shown in Fig. 1, no further explanation of the operation thereof will be given. It is deemed sufficient to state that the tension on the paper may be varied in response to variations in speed by partly closing throttle valve 44 or by substituting valve 44^a for valve 44 as shown in Fig. 4, that the tension on the paper 15 may be varied in response to the roll of paper increasing in diameter as shown in Fig. 5 or Fig. 6, and that the tension on the paper may be varied in response both to variations in speed and to variations in roll diameter by combining the circuits as shown in Fig. 7. The invention is susceptible of other modifications and adaptations 20 without departing from the scope thereof as hereafter claimed.

The invention is hereby claimed as follows:

25 1. The combination, with a machine from which sheet material is delivered at a speed proportional to the speed of said machine and a winder for winding said sheet into a roll, of a variable displacement hydraulic motor for driving said winder and maintaining tension upon said sheet, a metering pump driven in unison with said machine for supplying liquid to said motor and for controlling the rate at which liquid can be discharged therefrom, channel means connecting said pump and said motor and forming therewith a hydraulic circuit having pressure and return sides, an independently driven booster pump for delivering liquid into the pressure side of said circuit to thereby provide liquid in excess 30 of the requirements of said motor, a tension control valve connected to the pressure side of said circuit to permit liquid to escape therefrom after the pressure therein exceeds the resistance of said valve, and means for varying the displacement of said motor in response to variations in the pressure in the return side of said circuit.

35 2. The combination, with a machine from which sheet material is delivered at a speed proportional to the speed of said machine and a winder for winding said sheet into a roll, of a variable displacement hydraulic motor for driving said winder and maintaining tension upon said sheet, a metering pump driven in unison with said machine for supplying liquid to said motor and for controlling the rate at which liquid can be discharged therefrom, channel means connecting said pump and said motor and forming therewith a hydraulic circuit having pressure and return sides, an independently driven booster 40 pump for delivering liquid into the pressure side of said circuit to thereby provide liquid in excess of the requirements of said motor, a tension control valve connected to the pressure side of said circuit to permit liquid to escape therefrom after the pressure therein exceeds the resistance of said valve, means for varying the displacement of said motor in response to variations in the pressure in the return side of said circuit, and means for causing said motor to vary the tension on 45 said sheet in response to variation in the speed of said sheet.

50 3. The combination, with a machine from which sheet material is delivered at a speed proportional to the speed of said machine and a winder for winding said sheet into a roll, of a

variable displacement hydraulic motor for driving said winder and maintaining tension upon said sheet, a metering pump driven in unison with said machine for supplying liquid to said motor and for controlling the rate at which liquid 5 can be discharged therefrom, channel means connecting said pump and said motor and forming therewith a hydraulic circuit having pressure and return sides, an independently driven booster pump for delivering liquid into the pressure side 10 of said circuit to thereby provide liquid in excess of the requirements of said motor, a tension control valve connected to the pressure side of said circuit to permit liquid to escape therefrom after the pressure therein exceeds the resistance of 15 said valve, means for varying the displacement of said motor in response to variations in the pressure in the return side of said circuit, and means for causing said motor to vary the tension on said sheet in response to said roll increasing 20 in diameter.

4. The combination, with a machine from which sheet material is delivered at a speed proportional to the speed of said machine and a winder for winding said sheet into a roll, of a variable displacement hydraulic motor for driving said winder and maintaining tension upon said sheet, a metering pump driven in unison with said machine for supplying liquid to said motor and for controlling the rate at which liquid 25 can be discharged therefrom, channel means connecting said pump and said motor and forming therewith a hydraulic circuit having pressure and return sides, an independently driven booster pump for delivering liquid into the pressure side 30 of said circuit to thereby provide liquid in excess of the requirements of said motor, a tension control valve connected to the pressure side of said circuit to permit liquid to escape therefrom after the pressure therein exceeds the resistance of 35 said valve, means for varying the displacement of said motor in response to variations in the pressure in the return side of said circuit, and means for varying the resistance of said tension control valve in response to a variation in the speed of 40 said sheet to thereby cause said motor to vary the tension on said sheet.

5. The combination, with a machine from which sheet material is delivered at a speed proportional to the speed of said machine and a winder for winding said sheet into a roll, of a variable displacement hydraulic motor for driving said winder and maintaining tension upon said sheet, a metering pump driven in unison with said machine for supplying liquid to said 55 motor and for controlling the rate at which liquid can be discharged therefrom, channel means connecting said pump and said motor and forming therewith a hydraulic circuit having pressure and return sides, an independently driven booster 60 pump for delivering liquid into the pressure side of said circuit to thereby provide liquid in excess of the requirements of said motor, a tension control valve connected to the pressure side of said circuit to permit liquid to escape therefrom after 65 the pressure therein exceeds the resistance of said valve, means for varying the displacement of said motor in response to variations in the pressure in the return side of said circuit, and means for varying the resistance of said tension control 70 valve in response to said roll increasing in diameter to thereby cause said motor to vary the tension on said sheet.

6. The combination, with a machine from which sheet material is delivered at a speed pro-

portional to the speed of said machine and a winder for winding said sheet into a roll, of a variable displacement hydraulic motor for driving said winder and maintaining tension upon said sheet, a metering pump driven in unison with said machine for supplying liquid to said motor and for controlling the rate at which liquid can be discharged therefrom, channel means connecting said pump and said motor and forming therewith a hydraulic circuit having pressure and return sides, an independently driven booster pump for delivering liquid into the pressure side of said circuit to thereby provide liquid in excess of the requirements of said motor, a tension control valve connected to the pressure side of said circuit to permit liquid to escape therefrom after the pressure therein exceeds the resistance of said valve, means for varying the displacement of said motor in response to variations in the pressure in the return side of said circuit whereby motor displacement is increased and motor speed is decreased as said roll increases in diameter, and a third pump driven in unison with said motor for extracting a small volume of liquid from the return side of said circuit during each revolution of said motor to thereby cause said displacement varying means to increase the displacement of said motor by the amount necessary to enable said motor to have enough torque to overcome its own friction and the friction of said winder.

7. The combination, with a machine from which sheet material is delivered at a speed proportional to the speed of said machine and a winder for winding said sheet into a roll, of a variable displacement hydraulic motor for driving said winder and maintaining tension upon said sheet, a metering pump driven in unison with said machine for supplying liquid to said motor and for controlling the rate at which liquid can be discharged therefrom, channel means connecting said pump and said motor and forming therewith a hydraulic circuit having pressure and return sides, an independently driven booster pump for delivering liquid into the pressure side of said circuit to thereby provide liquid in excess of the requirements of said motor, a tension control valve connected to the pressure side of said circuit to permit liquid to escape therefrom after the pressure therein exceeds the resistance of said valve, means for varying the displacement of said motor in response to variations in the pressure in the return side of said circuit whereby motor displacement is increased and motor speed is decreased as said roll increases in diameter, a third pump driven in unison with said motor for extracting a small volume of liquid from the return side of said circuit during each revolution of said motor to thereby cause said displacement varying means to increase the displacement of said motor by the amount necessary to enable said motor to have enough torque to overcome its own friction and the friction of said winder, and means for causing said motor to vary the tension on said sheet in response to said roll increasing in diameter.

8. The combination, with a machine from which sheet material is delivered at a speed proportional to the speed of said machine and a winder for winding said sheet into a roll, of a variable displacement hydraulic motor for driving said winder and maintaining tension upon said sheet, a metering pump driven in unison with said machine for supplying liquid to said motor and for controlling the rate at which liquid

can be discharged therefrom, channel means connecting said pump and said motor and forming therewith a hydraulic circuit having pressure and return sides, an independently driven booster pump for delivering liquid into the pressure side of said circuit to thereby provide liquid in excess of the requirements of said motor, a tension control valve connected to the pressure side of said circuit to permit liquid to escape therefrom after the pressure therein exceeds the resistance of said valve, means for varying the displacement of said motor in response to variations in the pressure in the return side of said circuit whereby motor displacement is increased and motor speed is decreased as said roll increases in diameter, a third pump driven in unison with said motor for extracting a small volume of liquid from the return side of said circuit during each revolution of said motor to thereby cause said displacement varying means to increase the displacement of said motor by the amount necessary to enable said motor to have enough torque to overcome its own friction and the friction of said winder, and means for varying the resistance of said tension control valve in response to a variation in the speed of said sheet to thereby cause said motor to vary the tension on said sheet.

9. The combination, with a machine from which sheet material is delivered at a speed proportional to the speed of said machine and a winder for winding said sheet into a roll, of a variable displacement hydraulic motor for driving said winder and maintaining tension upon said sheet, a metering pump driven in unison with said machine for supplying liquid to said motor and for controlling the rate at which liquid can be discharged therefrom, channel means connecting said pump and said motor and forming therewith a hydraulic circuit having pressure and return sides, an independently driven booster pump for delivering liquid into the pressure side of said circuit to thereby provide liquid in excess of the requirements of said motor, a tension control valve connected to the pressure side of said circuit to permit liquid to escape therefrom after the pressure therein exceeds the resistance of said valve, means for varying the displacement of said motor in response to variations in the pressure in the return side of said circuit whereby motor displacement is increased and motor speed is decreased as said roll increases in diameter, a third pump driven in unison with said motor for extracting a small volume of liquid from the return side of said circuit during each revolution of said motor to thereby cause said displacement varying means to increase the displacement of said motor by the amount necessary to enable said motor to have enough torque to overcome its own friction and the friction of said winder, and means for varying the resistance of said tension control valve in response to said roll increasing in diameter to thereby cause said motor to vary the tension on said sheet.

10. The combination, with a machine from which sheet material is delivered at a speed proportional to the speed of said machine and a winder for winding said sheet into a roll, of a variable displacement hydraulic motor for driving said winder and maintaining tension upon said sheet, a metering pump driven in unison with said machine for supplying liquid to said motor and for controlling the rate at which liquid can be discharged therefrom, channel means connecting said pump and said motor and form-

- ing therewith a hydraulic circuit having pressure and return sides, an independently driven booster pump for delivering liquid into the pressure side of said circuit to thereby provide liquid in excess of the requirements of said motor, a tension control valve connected to the pressure side of said circuit to permit liquid to escape therefrom after the pressure therein exceeds the resistance of said valve, means for varying the displacement of said motor in response to variations in the pressure in the return side of said circuit, throttling means arranged in the return side of said circuit to cause a drop in pressure between two parts of said return side whereby said drop in pressure will vary in response to variation in the velocity of liquid in said return side caused by variation in the speed of said sheet, and means responsive to variations in said drop in pressure for varying the tension on said sheet.
- 20 11. The combination, with a machine from which sheet material is delivered at a speed proportional to the speed of said machine and a winder for winding said sheet into a roll, of a variable displacement hydraulic motor for driving said winder and maintaining tension upon said sheet, a metering pump driven in unison with said machine for supplying liquid to said motor and for controlling the rate at which liquid can be discharged therefrom, channel means connecting said pump and said motor and forming therewith a hydraulic circuit having pressure and return sides, an independently driven booster pump for delivering liquid into the pressure side of said circuit to thereby provide liquid in excess of the requirements of said motor, a tension control valve connected to the pressure side of said circuit to permit liquid to escape therefrom after the pressure therein exceeds the resistance of said valve, means for varying the displacement of said motor in response to variations in the pressure in the return side of said circuit, throttling means arranged in the return side of said circuit to cause a drop in pressure between two parts of said return side whereby said drop in pressure will vary in response to variation in the velocity of liquid in said return side caused by variation in the speed of said sheet, and means responsive to variations in said drop in pressure for varying the resistance of said tension control valve to thereby cause said motor to vary the tension on said sheet.
12. The combination, with a machine from which sheet material is delivered at a speed proportional to the speed of said machine and a winder for winding said sheet into a roll, of a variable displacement hydraulic motor for driving said winder and maintaining tension upon said sheet, a metering pump driven in unison with said machine for supplying liquid to said motor and for controlling the rate at which liquid can be discharged therefrom, channel means connecting said pump and said motor and forming therewith a hydraulic circuit having pressure and return sides, an independently driven booster pump for delivering liquid into the pressure side of said circuit to thereby provide liquid in excess of the requirements of said motor, a tension control valve connected to the pressure side of said circuit to permit liquid to escape therefrom after the pressure therein exceeds the resistance of said valve, means for varying the displacement of said motor in response to variations in the pressure in the return side of said circuit whereby motor displacement is increased and motor speed is decreased as said roll increases in diameter, a third pump driven in unison with said motor for extracting a small volume of liquid from the return side of said circuit during each revolution of said motor to thereby cause said displacement varying means to increase the displacement of said motor by the amount necessary to enable said motor to have enough torque to overcome its own friction and the friction of said winder, throttling means arranged in the return side of said circuit to cause a drop in pressure between two parts of said return side whereby said drop in pressure will vary in response to variation in the velocity of liquid in said return side caused by variation in the speed of said sheet, and means responsive to variations in said drop in pressure for varying the resistance of said tension control valve to thereby cause said motor to vary the tension on said sheet.
13. The combination, with a machine from which sheet material is delivered at a speed proportional to the speed of said machine and a winder for winding said sheet into a roll, of a variable displacement hydraulic motor for driving said winder and maintaining tension upon said sheet, a metering pump driven in unison with said machine for supplying liquid to said motor and for controlling the rate at which liquid can be discharged therefrom, channel means connecting said pump and said motor and forming therewith a hydraulic circuit having pressure and return sides, an independently driven booster pump for delivering liquid into the pressure side of said circuit to thereby provide liquid in excess of the requirements of said motor, a tension control valve connected to the pressure side of said circuit to permit liquid to escape therefrom after the pressure therein exceeds the resistance of said valve, means for varying the displacement of said motor in response to variations in the pressure in the return side of said circuit whereby motor displacement is increased and motor speed is decreased as said roll increases in diameter, a third pump driven in unison with said motor for extracting a small volume of liquid from the return side of said circuit during each revolution of said motor to thereby cause said displacement varying means to increase the displacement of said motor by the amount necessary to enable said motor to have enough torque to overcome its own friction and the friction of said winder, throttling means arranged in the return side of said circuit to cause a drop in pressure between two parts of said return side whereby said drop in pressure will vary in response to variation in the velocity of liquid in said return side caused by variation in the speed of said sheet, and means responsive to variations in said drop in pressure for varying the resistance of said tension control valve to thereby cause said motor to vary the tension on said sheet.
14. A drive, for driving a winder which winds sheet material into a roll as it is delivered thereto by a machine, comprising a variable displacement hydraulic motor for driving said winder and maintaining tension upon said sheet, means for supplying motive liquid to said motor to energize the same, means operated in response to said roll increasing in diameter for adjusting said motor to increase the displacement thereof, and means operated in response to operation of said motor adjusting means for varying the torque of said motor to thereby vary the tension on said sheet.
15. A drive, for driving a winder which winds sheet material into a roll as it is delivered thereto by a machine, comprising a variable displacement hydraulic motor for driving said winder and maintaining tension upon said sheet, means for supplying motive liquid to said motor to energize

- the same, means operated in response to said roll increasing in diameter for adjusting said motor to increase the displacement thereof, a resistance valve, means for directing liquid through said resistance valve, means for varying the torque of said motor in response to a drop in pressure across said resistance valve, and means responsive to operation of said motor adjusting means for varying the resistance of said resistance valve to vary 5 the drop in pressure thereacross and thereby vary the tension on said sheet as said roll increases in diameter.
16. A drive, for driving a winder which winds sheet material into a roll as it is delivered thereto by a machine, comprising a variable displacement hydraulic motor for driving said winder and maintaining tension upon said sheet, means for supplying motive liquid to said motor to energize the same, means operated in response to said roll 10 increasing in diameter for adjusting said motor to increase the displacement thereof, and means for increasing the torque of said motor during acceleration thereof without affecting the operation of said motor adjusting means.
17. A drive, for driving a winder which winds sheet material into a roll as it is delivered thereto by a machine, comprising a variable displacement hydraulic motor for driving said winder and maintaining tension upon said sheet, means for supplying motive liquid to said motor to energize the same, means operated in response to said roll 15 increasing in diameter for adjusting said motor to increase the displacement thereof, and means responsive to said motor being accelerated for increasing the torque of said motor during acceleration without affecting the operation of said motor adjusting means.
18. A drive, for driving a winder which winds sheet material into a roll as it is delivered thereto by a machine, comprising a variable displacement hydraulic motor for driving said winder and maintaining tension upon said sheet, means for supplying motive liquid to said motor to energize the same, means operated in response to said roll 20 increasing in diameter for adjusting said motor to increase the displacement thereof, and means responsive to said motor being accelerated or decelerated for increasing the torque of said motor during acceleration and decreasing it during deceleration without affecting the operation of said motor adjusting means.
19. A drive, for driving a winder which winds sheet material into a roll as it is delivered thereto by a machine, comprising a variable displacement hydraulic motor for driving said winder and maintaining tension upon said sheet, pumping means for supplying liquid to said motor at a rate in excess of motor requirements, channel 25 means connecting said pumping means to said motor and forming therewith a hydraulic circuit having pressure and return sides, a tension control valve connected to the pressure side of said circuit to permit liquid to escape therefrom after the pressure therein exceeds the resistance of said valve, and means responsive to said motor being accelerated for increasing the resistance of said valve during acceleration.
20. A drive, for driving a winder which winds sheet material into a roll as it is delivered thereto by a machine, comprising a variable displacement hydraulic motor for driving said winder and maintaining tension upon said sheet, pumping means for supplying liquid to said motor at a rate in excess of motor requirements, channel 30 means connecting said pumping means to said motor and forming therewith a hydraulic circuit having pressure and return sides, a tension control valve connected to the pressure side of said circuit to permit liquid to escape therefrom after the pressure therein exceeds the resistance of said valve, and means responsive to said motor being accelerated or decelerated for increasing the resistance of said valve during acceleration.
21. The combination, with a machine from which sheet material is delivered at a speed proportional to the speed of said machine and a winder for winding said sheet into a roll, of a variable displacement hydraulic motor for driving said winder and maintaining tension upon said sheet, a metering pump driven in unison with said machine for supplying liquid to said motor and for controlling the rate at which liquid can be discharged therefrom, channel means 35 connecting said pump and said motor and forming therewith a hydraulic circuit having pressure and return sides, an independently driven booster pump for delivering liquid into the pressure side of said circuit to thereby provide liquid in excess of the requirements of said motor, a tension control valve connected to the pressure side of said circuit to permit liquid to escape therefrom after the pressure therein exceeds the resistance of said valve, means for varying the displacement of said motor in response to variations in the pressure in the return side of said circuit, means for causing said motor to vary the tension on said sheet in response to variation in the speed of said sheet, and means for causing said motor to vary 40 the tension on said sheet in response to said roll increasing in diameter.
22. The combination, with a machine from which sheet material is delivered at a speed proportional to the speed of said machine and a winder for winding said sheet into a roll, of a variable displacement hydraulic motor for driving said winder and maintaining tension upon said sheet, a metering pump driven in unison with said machine for supplying liquid to said motor and for controlling the rate at which liquid can be discharged therefrom, channel means connecting said pump and said motor and forming therewith a hydraulic circuit having pressure and return sides, an independently driven booster pump for delivering liquid into the pressure side of said circuit to thereby provide liquid in excess of the requirements of said motor, a tension control valve connected to the pressure side of said circuit to permit liquid to escape therefrom after the pressure therein exceeds the resistance of said valve, means for varying the displacement of said motor in response to variations in the pressure in the return side of said circuit whereby motor displacement is increased and motor speed is decreased as said roll increases in diameter, a third pump driven in unison with said motor for extracting a small volume of liquid from the return side of said circuit during each revolution of said motor to thereby cause said displacement varying means to increase the displacement of said motor by the amount necessary to enable said motor to have enough torque to overcome its own friction and the friction of said winder, and means for causing said motor to vary the tension on said sheet in response to variation in the speed of said sheet.
